UNITED STATES PATENT OFFICE.

ADAM E. SCHATZ, OF NEW YORK, N. Y.

TELEPHONE SOUND-TRANSMITTER.

SPECIFICATION forming part of Letters Patent No. 449,180, dated March 31, 1891.

Application filed March 1, 1888. Serial No. 265,824. (No model.)

To all whom it may concern:

Be it known that I, ADAM E. SCHATZ, a citizen of the United States, and a resident of New York city, in the county of New York and State of New York, have invented certain new and useful Improvements in Telephone Sound-Conveyers, of which the following is a specification.

My invention relates to improvements in instruments intended to convey the sound of the voice to the sound-transmitter of telephonic instruments; and the objects of my improvements are the exclusion of other surrounding foreign noises, thus enabling the speaker to more distinctly convey the message to the hearer and in such a low tone of voice that conversation may be had without persons near by hearing the same, and thus also preventing eavesdropping. I attain these objects by the instrument illustrated in the accompanying drawings, in which—

Figure 1 is a longitudinal cross-section. Fig. 2 is a longitudinal plan view showing the instrument attached to a telephone-instrument, ready for use. Fig. 3 shows one of the modes in which the instrument may be affixed to the telephone-instrument.

Similar letters refer to similar parts throughout the several views.

30 A is an ordinary cattle-horn, having the open ends a' and a^3 and the opening a^2 cut into the outer or convex side of the horn near the open end a' and the cushion or elastic tip a at the small end of the horn. This tip a is provided for the purpose of tightly setting the end into the recess of the telephone-transmitter T^2 . The opening a^3 of the instrument is preferably made of the same diameter as the opening t of the transmitter T^2 , so that 40 the sound-wave may not be disturbed and may glide uninterrupted, to further facilitate which the interior of the horn is smoothed.

In use the horn or instrument may be held in the hand in any convenient position with 45 the small end a^3 set in the recess of the transmitter T^2 . The opening a^3 is brought closely to the mouth of the speaker, and the voice-sound is emitted into the instrument and is thrown against the wall of the inner or convex side of the horn tangentially inward, and is crowded to the mouth a^3 and into the

transmitter, the surplus sound being forced out at the opening a' .

It is to be understood that in use, when it is desired to prevent persons near by from overhearing the user's voice or to prevent eavesdropping, the user will talk very low, and the sound-waves, owing to the peculiar shape of the horn, will nearly all pass to the transmitter, and those waves which pass out 60 through opening a' will be insufficient to be overheard; but this opening a' is necessary, for in case of even a very slight surplus of sound, such sound would be returned from a closed end, and thereby interfere with the 65 sound-waves passing to the transmitter. In case of loud talking the necessity of the opening a' is the more apparent.

The upper portion of the body of the person speaking into the opening a^2 of the cattle-horn A is in such close proximity to the large opening a' at the bottom of the cattle-horn as to practically form a shield or sound-breaker, which will effectually prevent eavesdropping while the speaker is using the instrument. This position of the instrument is not shown, because I find it more convenient to attach the instrument in the manner shown in Fig. 2, although the manner shown in Fig. 3, in which the instrument is provided 80 with a recess b into and around which is fitted the rubber disk-shaped tip c , which disk c may be fastened to the telephone transmitter for the purpose of holding the horn in place, or any other manner of holding the instrument A may be employed. I may also cut the opening a^2 in any side of the instrument A without very materially departing 85 from its effectiveness. It is obvious that the instrument may be made of any material. 90

I am aware that trumpet-like instruments, in which the voice is thrown into the large mouth, have been used for the same purpose, but none to my knowledge have been used constructed on the plan shown in my drawings and specification. 95

What I claim as new, and desire to secure by Letters Patent, is—

1. The horn-shaped sound-conveyer for telephones, provided with an opening a^2 in 100 its convex side near the large open end thereof, substantially as described.

2. A sound-conveyer for telephones, consisting of a horn-shaped mouth-piece open at both ends and having an opening in its convex side intermediate of its ends, the small end being provided with an elastic tip, substantially as described.

Signed at New York, in the county of New

York and State of New York, this 18th day of February, A. D. 1888.

ADAM E. SCHATZ.
